UNITED STATES PATENT OFFICE.

MILES G. NIXON, OF CHICAGO, ILLINOIS.

DESIGN FOR A PISTOL-GUIDE.

59,861.

Specification for Design.

Patented Nov. 29, 1921.

Application filed March 7, 1918. Serial No. 221,080. Term of patent 14 years.

To all whom it may concern:

Be it known that I, MILES G. NIXON, a citizen of the United States, of Chicago, in the county of Cook, and in the State of Illinois, have invented a new, original, and ornamental Design for Pistol-Guides, and do hereby declare that the following is a full, clear, and exact description thereof.

Referring to the accompanying drawing which forms a part of this specification:

Figure 1 is a side elevation of my new design;

Fig. 2 is a cross section on the line 2—2 of Fig. 1.

The essential feature of my design is the shape or configuration of the guide.

My design is for a pistol guide. In order to show its relation to the pistol, when applied, the pistol members are shown in dotted lines.

I claim—

The ornamental design for a pistol guide substantially as shown and described.

MILES G. NIXON.
